UNITED STATES PATENT OFFICE.

WILLIAM H. MOORE, OF WAVELAND, INDIANA.

GUARD-RAIL.

No. 805,928.

Specification of Letters Patent.

Patented Nov. 28, 1905.

Application filed August 29, 1905. Serial No. 276,298.

To all whom it may concern:

Be it known that I, WILLIAM H. MOORE, a citizen of the United States of America, residing at Waveland, in the county of Montgomery and State of Indiana, have invented new and useful Improvements in Guard-Rails, of which the following is a specification.

This invention relates to improvements in guard-rails, and has for its object to provide 10 a guard-rail which is simple, strong, durable, and inexpensive of construction and provided with means to secure a bracing action between the same and the main rail to strengthen the connection and maintain the 15 two rails in properly-spaced relation, as well as to so construct the ends of the guard-rail as to guide the flanges of a wheel between the rails in a reliable manner and with a reduction of strain upon the guard-rail.

20 In the accompanying drawings, Figure 1 is a plan view of my improved guard-rail applied to the adjoining section of a main rail. Fig. 2 is an inner elevational view of the guard-rail, the supporting-ties appearing in 25 transverse section; and Figs. 3 and 4 are cross-sections taken, respectively, on the lines 3 3 and 4 4 of Fig. 1.

Referring now more particularly to the drawings, the numeral 1 designates a main or 30 track rail of an ordinary steam-railway or street-railway, and 2 the guard-rail, arranged contiguous to the main rail opposite the frog, (not shown,) the opposite ends of the guard-rail being inwardly curved or turned 35 in the usual manner, as indicated at 3.

The rail 2 is provided with openings for the 40 passage of bolts 4, connecting it with the rail 1 and is adapted to rest upon the cross-ties, to which it may be spiked or otherwise secured, if desired. A bracing-projection 5, comprising a lug or offset, extends from the outer side 45 of the rail 2 and bears against the head and web of the rail 1, as clearly indicated in Fig. 3, thus spacing the center of the guard-rail from the adjacent portion of the main rail, so as to hold the two in determined relation. Formed upon the ends of the guard-rail are webs 6, which bear against the web and adjacent portions of the foot of the rail 50 1 and thence curve outwardly to the inturned ends 3, the outer faces of which latter are beveled or inclined, as shown at 7, in order to form a more effective guide for the wheels of a derailed car. The central bracing projec-

tion 5 and web 6, which constitute terminal 55 bracing projections, are integral with the guard-rail 2 and have their lower faces arranged above the base of said rail and the base of the main rail 1, so as to provide for the reception of the heads of the spikes securing the 60 main rail to the ties.

If desired, the guard-rail may be provided between the central bracing projection 5 and each web 6 with a flange or rim 8, adapted to be engaged by the heads of spikes to secure 65 the rail to the immediately underlying ties, so that in case the fastening-bolts become loose the guard-rail will still be firmly held in position.

It will be observed that the guard-rail is 70 simple in construction and comparatively inexpensive of production and while formed independent of the main rail practically constitutes a part thereof, as the bracing connections and bolts hold the two rails securely 75 connected in proper relation and prevent independent movement thereof. The edges are secured without the necessity of making the guard-rail an integral part of the main rail—a construction practically infeasible for 80 reasons well known in the art.

It will be apparent that the curved or beveled surfaces of the webs 6 will render it impossible for train hands or others to get 85 their feet caught between the rails, as such surfaces are devoid of angles or shoulders in which the foot can become wedged, but allow the foot to slip out. Hence this construction will prevent the loss of life and limbs, due in the ordinary construction of guard- 90 rail to the inability of a person whose foot is caught to extricate his foot in time to avoid being run down by passing trains or rolling-stock.

Having thus described the invention, what 95 is claimed as new is—

1. A guard-rail provided with central and terminal projections to space it from the main rail.

2. A guard-rail having inturned ends, a 100 central spacing projection, a terminal spacing projection formed upon the inturned ends, said projections being adapted to engage the main rail and space the guard-rail therefrom.

3. A guard-rail provided with inturned ends having beveled outer faces, and terminal projections extending from the outer face

thereof to bear upon the main rail, said projections forming continuations of the beveled surfaces of the inturned ends.

4. The combination with a main rail, of a
5 guard-rail having spacing projections bearing
upon the main rail, and bolts connecting said
rails intermediate said projections.

In testimony whereof I affix my signature
in presence of two witnesses.

WILLIAM H. MOORE.
